CARBURETOR

Milton E. Chandler and Emil O. Wirth, South Bend, Ind., assignors to Bendix Aviation Corporation, South Bend, Ind., a corporation of Delaware

Application December 1, 1933, Serial No. 700,537

5 Claims. (Cl. 261—34)

This invention relates to carburetors, and more particularly to acceleration pumps used in association with carburetors.

In designing a carburetor, it is desirable to so locate the acceleration pump that it will quickly inject a charge of liquid fuel when the throttle is opened rapidly. It is desirable to have the charge of fuel which is injected for acceleration purposes distributed over a period of several seconds, so graduated that a greater quantity is injected at first and a decreasing quantity over the remaining portion of said period.

An object of the present invention is to produce a carburetor having an acceleration pump of the type above mentioned, which will be of simplified and improved design and economical to manufacture.

A further object of this invention is to provide an improved carburetor in which the fuel pump is cast integral with the body of the carburetor, and equipped with a yielding means such that the aforesaid desirable control of the charge of liquid fuel injected for acceleration purposes may be obtained.

A further object of this invention is to eliminate all possibility of leaks of air or fuel from the acceleration pump.

The above and other desirable novel features of this invention will appear more fully hereinafter from the following detailed description, when taken in connection with the accompanying drawings. It is expressly understood, however, that the drawings are employed for purposes of illustration only, and are not designed as a definition of the limits of the invention, reference being had for that purpose to the appended claims.

In the drawings:

Figure 1 is an elevation of a carburetor unit embodying the invention, showing the operating mechanism of the acceleration pump;

Figure 2 is a plan view of the carburetor unit showing the location of the acceleration pump;

Figure 3 is a vertical section taken on line 3—3 of Figure 2;

Figure 4 is a sectional view showing a modified form of acceleration pump piston;

Figure 5 is a view similar to Figure 4, but showing a further modification of the accelerating pump piston;

Figure 6 is a sectional view showing a further modification of the pump and the manner of venting the float chamber and acceleration pump to the air horn.

Referring more particularly to Figure 1, there

is shown, for purposes of illustrating this invention, a downdraft carburetor comprising an upper body section 10 and a lower body section 12. A choke valve 14 operated by an actuating mechanism 16 controls the amount of air admitted through the air horn 18. A throttle valve 20 manually controlled in the usual manner by means of an actuating mechanism 22, governs the amount of combustible mixture admitted to the intake manifold of the engine through the carburetor outlet 24.

The acceleration pump unit is cast integral with the float chamber 26 and upper section 10 of the carburetor. It consists of a hollow cylinder 28 in which is mounted a piston 30, comprising a disk 32, a leather washer 34, and a coiled helical spring 36 to expand said washer 34 into contact with the walls of cylinder 28. The piston is mounted on a rod 38 which is circumferentially wound by two coil springs 40 and 42, being separated by a washer 44 slideable on rod 38. These springs are held in compression by a nut 46 screwed to the end of rod 38. Rod 38 is actuated by a plunger actuating rod 48 having at its upper end an arm 50 apertured to encircle rod 38 in slideable relation, so that it will compress springs 40 and 42 when rod 48 is drawn downwardly. The means for drawing rod 48 downwardly comprises an arm 52 fixed to the throttle shaft 54 on the opposite side of the main carburetor passage to the throttle actuating mechanism 22, and a link 56 connecting arm 52 with rod 48.

The acceleration pump discharges through an outlet passage 58, controlled by a valve 60 which is yieldingly held closed by a spring 62. Passage 58 connects with passages 64 and 66 which lead to the acceleration pump nozzle 68, discharging into a primary venturi 70 in the main carbureting passage. Since arm 52 is fixed to throttle shaft 54, it will rotate therewith and impart movement to link 56, which will in turn actuate rod 48, compressing springs 40 and 42. The pressure exerted by the springs will urge piston 30 downwardly, and the resulting pressure on the fuel in cylinder 28 will compress spring 62, unseat valve 60 and allow fuel to flow to the acceleration fuel nozzle 68.

Since spring 42 is weaker than spring 40, the initial movement of arm 48 will compress it to the limit of its movement, and the force then exerted by piston 30 upon the fuel will then depend upon the reaction of the stiffer spring 40, which will cause a greater quantity of fuel to flow during the early stages of the action. Spring 40 will expand first, giving a sustained flow dur-

- ing the middle portion of the period, and spring 42 will expand last, giving a decreased rate of flow during the latter stages of the action. At full open throttle a retaining member 72 on piston 30 holds valve 60 open by contacting the end of its stem 74, allowing the fuel to continue to flow through the above-enumerated passages to nozzle 68, giving a richer mixture for full power operation.
- 10 Figure 4 illustrates a modified acceleration pump piston which may be used instead of the piston illustrated in Figure 3. It incorporates a relief valve, and consists essentially of a piston rod 80 to which is fixed a plunger 82 having a bore 84 drilled longitudinally from the top to accommodate a check valve comprising a ball 86 held on its seat by a spring 88. An upper passage 90 and a lower passage 92 are drilled transversely through plunger 82 and communicate 15 with bore 84 respectively above and below the check valve. An annular groove 94 cut around the circumference of plunger 82 accommodates a coil spring 96 which urges facing material 98 against the wall of the cylinder 100.
- 20 25 As the piston slides down cylinder 100 under action of the actuating mechanism, which may be of any suitable type, pressure will be exerted through groove 94 and passage 92 upon said check valve and when the pressure rises sufficiently to 30 overcome the resistance of spring 88, fuel will flow past ball 86 and through passages 84 and 90. Therefore, when the pressure rises above a certain value, dependent upon the stiffness of spring 88, a portion of the fuel will be by-passed through 35 the piston and back to the supply chamber to prevent choking the engine with an excessive charge of raw fuel. When the engine is accelerated slowly no fuel will be by-passed, however, as the pressure will not be sufficient to operate the check 40 valve, and a prolonged discharge suitable for acceleration purposes will thereby be obtained.
- Figure 5 illustrates a modification of an acceleration pump, embodying an internal pressure responsive mechanism, consisting essentially of a cylinder 110 having a compound piston 112 slideable therein. Piston 112 comprises a body portion 114, drilled to accommodate a small internal piston 116 slideable therein and yieldingly urged to the lower extremity of said body portion by spring 45 118. Piston head 120 is provided with an annular groove 122 which receives a coil spring 124 to urge the facing 126 of said piston against the walls of cylinder 110, said facing being made of any suitable material such as leather, and held 50 in place by compression between the piston head 120 and body portion 114 which are screwed together.
- Piston 112 is provided with an actuating rod 128 connected thereto through pivotal joint 130. 60 The pump outlet is provided with a check valve 132 which is similar in construction and operation to that disclosed in connection with Figure 3. An internal piston 116 is mounted within a cylindrical bore 134 of piston 112 and is provided with 65 a stud 136 for the purpose of engaging stem 138 of check valve 132 when piston 112 is held in its lowermost position, to hold said valve open and permit a continuous flow of fuel through said valve to the fuel discharge nozzle, supplying a 70 rich mixture for full power operation of the engine.

The operation of the device shown in Figure 5 is as follows. The actuating rod 128 is connected by means of any suitable mechanism to the throttle shaft, or to a piston operated by the

varying suction posterior to the throttle, so that as the throttle is opened, piston 112 slides downwardly in cylinder 110 compressing the entrained fuel and forcing check valve 132 open. Since the quantity of fuel which can pass through check valve 132 is limited by the area of the opening and size of ducts leading therefrom a method of relieving excessive pressure is provided so that the throttle will not be restricted in its operation. When the pressure builds up in the cylinder 110 below the piston 112 sufficiently to overcome the resistance offered by spring 118, piston 116 will slide upward in bore 134 and permit fuel to fill the chamber 135 below the piston 116. When sufficient fuel has passed through check valve 132 to relieve the pressure sufficiently, piston 116 will be forced downwardly by spring 118 and when it reaches the end of cylindrical bore 134, if the throttle is held in open position, stud 136 will engage valve stem 138 and hold valve 132 open, permitting a continuous flow of fuel through said valve to the acceleration fuel discharge nozzle.

As the throttle valve is closed, piston 112 will be drawn upwardly in cylinder 110 by rod 128, permitting check valve 132 to close to prepare the acceleration pump for the next operation.

Figure 6 illustrates a vacuum operated acceleration pump, and a vent from the air horn to the acceleration pump and float chamber.

The acceleration pump comprises an upper cylinder 150 and a lower cylinder 152 which are separated by means of a washer 154. The upper cylinder 150 houses a piston 156 which is yieldingly urged to the lower extremity of said cylinder by means of a spring 158. The top of cylinder 150 communicates with the main carbureting passage 160, posterior to the throttle valve 162 by means of a duct 164 which subjects cylinder 150 to the partial vacuum existing at that point during certain conditions of operation of the engine.

The lower cylinder 152 also houses a piston 166 which is yieldingly urged to the lower extremity of cylinder 152 by spring 168 operating between a facing 170 fixed to rod 172 and washer 154 separating the two cylinders. Rod 172 is pivotally connected at its upper end with piston 156 of upper cylinder 150 by a universal joint 174 of known construction. Piston 166 in the lower cylinder is fitted with a leather washer 176 which is yieldingly urged into contact with cylinder 152 by means of a helical coiled spring 178.

A check valve is incorporated in the piston 166, consisting of a horizontal fuel passage 202 connecting with a vertical passage 204 which discharges into a circular bore 206 drilled piston 166, and closed by a flat plate 180 having holes 208 drilled therein to permit fuel to flow. A disc 210 is free to move in circular bore 206 and rests upon flat plate 180 by gravity except when the pump is in operation, at which time the pressure of the entrained fuel will force disc 210 up, closing vertical passage 204 to prevent fuel from escaping. This construction permits the acceleration pump to be filled through a port 212 communicating with the float chamber 200 below the fuel level X—X, since said flat disc 210 permits fuel to flow through piston 166 at all times except when said piston is actuated downwardly. Plate 180 is designed to engage valve stem 138 of an economizer valve 182 fitted in the bottom of cylinder 152, which valve is of a construction similar to that disclosed in connection with Figure 3. A fuel duct 184 leads from economizer valve 182 to the fuel discharge nozzle 186 in the main carbureting passage 160 of the carburetor.

Cylinder 152 is provided with a vent 187 which communicates by means of duct 188 with an annular groove 190 formed between the body section 192 of the carburetor and the venturi 194. A passage 196 leads from groove 190 to the air horn anterior to the choke valve 198. Duct 188 has a branch 189 which terminates in the float chamber 200 above the fuel level X—X.

The operation of the device shown in Figure 6 is as follows. When the engine is idling a partial vacuum exists in the main carbureting passage 160 posterior to throttle valve 162. This suction is transmitted by means of duct 164 to cylinder 150 of the acceleration pump and will cause piston 156 to slide upward in said cylinder, compressing spring 158 and carrying with it piston 166 fixed to rod 172, by means of the joint 174, and compressing spring 168.

When throttle valve 162 is opened, the partial vacuum is destroyed, and as the suction exerted on piston 156 drops below that required to keep springs 158 and 168 compressed, piston 156 will slide downwardly in cylinder 150, leaving piston 166 free to move downwardly in cylinder 152 under the influence of spring 168, exerting pressure on the entrained fuel, which will open the economizer valve 182 and pass through duct 184 to the fuel discharge nozzle 186.

If the throttle is moved from closed position to full open position quickly, piston 156 will be quickly forced to the bottom of cylinder 150 by spring 158, and piston 166 will slide downward in cylinder 152 less quickly under action of spring 168. Since the opening through the economizer valve is restricted, an interval of time will be required before the piston 166 reaches the end of its stroke, so that a sustained discharge will be obtained. When throttle valve 162 is closed again a partial vacuum will be created in the main carbureting passage posterior to the throttle valve which when transmitted to cylinder 150 through duct 164 will cause piston 156 to move upwardly. During this upward movement, plate 210 permits fuel to flow through passage 204 to the space below piston 166 to prepare the pump for the next operation. An adjusting pin 214 is threaded through a plug 216 in the upper end of cylinder 150 and projects therefrom to form an adjustable stop for piston 156, to permit the stroke of the pump to be varied as desired.

As previously noted, cylinder 152 is provided with a vent 187 which equalizes the pressure in the acceleration pump cylinder, float chamber and air horn, thus insuring uniform operation, and providing air which has passed through the air cleaner (not shown) commonly connected to the air horn.

We claim:

1. In a carburetor, an acceleration pump comprising a cylinder, a piston therein, a piston rod

connected to said piston, an actuating member slidable on said piston rod, and a plurality of springs of different resiliency connected in series between the actuating member and piston.

2. In a carburetor having a body portion forming a main carbureting passage, a float chamber, an acceleration pump having a cylinder formed integral with said body portion and float chamber, mechanism for actuating said acceleration pump including a member fixed to one end of the throttle shaft, a rod connected to said member having an arm thereon, a piston rod associated with said pump and slidable within an aperture in said arm, and a plurality of coil springs of different stiffness wound around said piston rod and connected in series in such manner that the acceleration pump discharges a gradually decreasing sustained flow of liquid fuel as the throttle valve is actuated.

3. In a carburetor, an acceleration pump comprising a cylinder, a piston slidable in said cylinder, a piston rod, an arm fixed to the throttle shaft, an actuating member between said arm and said piston rod and slidable thereon, and a plurality of springs of different resiliency associated with said piston rod and forming an actuating connection between the actuating member and the piston.

4. In a carburetor, an induction passage, a throttle valve, means to actuate the throttle valve, a fuel reservoir, a main fuel nozzle, an auxiliary fuel nozzle, acceleration means to discharge fuel from the reservoir into the induction passage through the auxiliary fuel nozzle upon opening movement of the throttle valve, said acceleration means including a cylinder positioned in the fuel reservoir and communicating with the induction passage, a piston having a stem movable in the cylinder, and a yielding connection including a plurality of coaxially wound springs of varying resiliency surrounding the stem of the piston and connected with the throttle actuating means.

5. In a carburetor, an induction passage, a throttle valve controlling the induction passage, manual means to actuate the throttle valve, a fuel reservoir, means including a cylinder positioned in the fuel reservoir and communicating with the reservoir and the induction passage, a throttle controlled piston movable in the cylinder for supplying a quantity of fuel to the induction passage under certain operating conditions, and yielding means including a plurality of springs of different resiliency between the throttle controlled piston and the throttle to vary the rate of flow of fuel discharged from the cylinder.
